Specification of Letters Patent.

Patented May 4, 1915.

Application filed October 24, 1914. Serial No. 868,400.

To all whom it may concern:

Be it known that I, ALBERT A. PAGE, a citizen of the United States, residing in East Haven, county of New Haven, and State of Connecticut, have invented certain new and useful Improvements in Locks, of which the following is a full, clear, and exact description.

This invention relates to locks, and more particularly to latch bolt locks for school-houses and other buildings, having means operable by a key whereby the latch bolt may be dogged in its retracted position so that when desired the door may be opened merely by pushing or pulling the same.

One of the primary objects of the present invention is to provide a lock having a cylinder lock mechanism of the ordinary pin tumbler type, operable from one side of the door by at least two different keys, together with mechanism which will dog the latch bolt in retracted position when said cylinder lock is actuated by one of said keys, without so dogging it when said cylinder lock mechanism is actuated by the other key, which latter key will retract the bolt but will not cause it to be held back in the inoperative position. Thus this last named key may be used by the teachers, or other persons to whom it is not desired to give control of the latch dogging mechanism, while the first key can be retained by the janitor, or other authorized person to whom it is desired to give such control. Therefore there is no likelihood of the teacher's key being so used as to leave the door in unlocked condition at a time when it should be locked against intrusion. Usually the janitor's key will be operative to retract the latch bolt, as well as to dog it in the retracted position, but this is not necessary in all aspects of the invention. It will be understood that both keys are used in connection with the same cylinder, which is preferably at the outside of the door, and the teacher's key is, for all practical purposes, a change key, while the janitor's key is in a sense a master key.

Another object of the invention is to provide a lock in which the latch bolt, after being dogged in retracted position by the master key, cannot be released by the change key. In other words, the release of the latch

bolt from its dogged position, as well as the dogging of the same in retracted position, is confined to the master key.

55

A still further object which I have in view is the provision of a lock in which a single cylinder is so constructed and arranged relative to the lock parts that one of the roll-backs will dog and release the latch, while another rollback will not, under any conditions, perform any function except that of withdrawing the latch to open the door.

To these and other ends, the invention consists in the novel features and combinations of parts to be hereinafter described and claimed.

In the accompanying drawings, Figure 1 is an elevation of a lock embodying my improvements, with the cap plate removed, the parts being shown in the normal position; Fig. 2 is a fragmentary view similar to Fig. 1, showing the latch bolt fully retracted by the teacher's key; Fig. 3 is a section on line 3—3 of Fig. 1, showing the teacher's key inserted into the cylinder lock; Fig. 4 is a view similar to Fig. 2, showing the latch bolt retracted by the janitor's key; Fig. 5 is a section similar to Fig. 3, showing the janitor's key inserted into the cylinder lock; Fig. 6 is a fragmentary view of the lock mechanism showing how the teacher's key is inoperative to release the latch bolt from its dogged position; and Fig. 7 comprises an edge view of the main retracting lever and a face view thereof.

Referring to the drawings, the case 10 of the lock having the face plate 11 contains a latch bolt 12 normally projected by a spring 13. The stem 14 of the bolt carries a head 15 engaged by a lever 16 adapted to be operated by a lifter 17, which is in turn actuated by an inside thumb piece, push bar, or other mechanism (not shown). The particular means for retracting the latch bolt manually from the inside of the door is immaterial. In the particular lock selected for illustration, the retraction of the bolt from the outside of the door is confined to the key, but this is likewise an immaterial feature so far as this invention is concerned.

The means for retracting the latch bolt by means of a key comprises a latch bolt-retracting lever 20, pivoted in the case at 21,

and having one extremity 22 thereof engaged with the cross-head 15 of the bolt. The retracting lever 20 is provided with a projection 23 engaged by an arm 24 of a main detent lever 25, pivoted in the case at 26. The extremity 24^a of the arm 24 extends transversely across the case in operative relation to a bit, dog or rollback 27 of a cylinder lock 28 inserted in a suitable opening in the case, usually at the outside of the door. The cylinder lock 28 also has another bit, dog or rollback 29 rotatable in a plane offset from the plane of the projection 24^a and adapted to engage the free end 30 of a lever 31, pivoted in the case at 32. The end 30 of lever 31 loosely rests on and is supported by a lateral projection 33 on the lever 20. The parts are so arranged that when the bit or rollback 29 is turned in a counter-clockwise direction with respect to Fig. 1, it will be unable to contact with the projection 24^a of lever 25, but will, on the other hand, depress the lever 31 and actuate the lever 20 to retract the latch bolt without moving the lever 25, as shown more particularly in Fig. 2.

The cylinder lock 28 illustrated in the drawing is provided with a key plug 34 surrounded by an eccentric sleeve 35. The ordinary pin tumblers 36 coöperate with this key plug and sleeve in the customary manner, as shown. In the particular form illustrated, the bit or rollback 27 is secured to the key plug 34 by means of the screws 37, while the bit or rollback 29 is secured to the sleeve 35 by the screws 38. It will be obvious that the center of rotation of the key plug and therefore of the rollback 27 is somewhat lower than the center of rotation of the sleeve 35 and rollback 29.

The arm 24 of the lever 25 is made of special shape so that as said arm is actuated by the rollback 27, it may operate to hold the latch bolt in its retracted position. To this end, the edge portion of the arm 24, co-acting with the projection 23 of the latch bolt lever, is formed with a shoulder 39 having inclined edges 40, 41 directed at an angle to each other to create a pointed projection, as shown. As the latch bolt is retracted by the lever 25, the edge 40 of said shoulder or projection 23 bears against the projection 23 when the arm 24 moves toward the right with reference to Fig. 1. As the movement of the arm 24 continues, the shoulder 39 and projection 23 move relatively to each other in such a manner that as soon as the latch bolt has been fully retracted, the projection 23 on the lever 20 passes the apex of the shoulder 39 and snaps into position against the edge 41 of said shoulder, whereby the lever 25 and the latch bolt 12 are locked in retracted position. In order to increase the security with which the latch bolt is dogged in this position, the detent lever 25 is pro-

vided with a rearwardly directed extension 42, which as the projection 23 passes from one side to the other of the shoulder 39, snaps into position in front of the cross-head 15 and engages said cross-head frictionally, as shown in Fig. 4. In this manner, the latch bolt is held securely in retracted position, and it will remain in said position until the rollback 27 is rotated in a direction opposite to that first indicated, in order to cause the abutment of the rollback 27 against the opposite side of the projection 24^a and the release of the lever 25, whereupon the parts will be restored by the latch bolt spring to the initial position.

The teacher's key, or change key 39, is adapted to rotate the key plug 34 and sleeve 35 together, and consequently it rotates both rollbacks 27 and 29 at the same time. These rollbacks in this case both rotate about the axis of the sleeve, as will be understood. When the rollbacks are rotated in a counter-clockwise direction with reference to Fig. 1, the latch bolt will be retracted by means of the levers 31 and 20, as hereinbefore described, without affecting the detent lever 25, so that as a consequence the teacher's key is inoperative to hold the latch bolt retracted by means of said detent lever. The latch bolt is fully retracted before the rollback 27 reaches the extremity 24^a of the lever 25, as shown in Fig. 2.

The master key, or janitor's key 40, rotates the key plug 34 individually, and hence when said key is inserted and turned in the lock the rollback 27 will be actuated, but the rollback 29 will remain stationary. When the rollback 27 is rotated in a counter-clockwise direction with respect to Fig. 1, it will abut the extremity 24^a of the lever 25 and actuate said lever 25 in a manner previously described so as to first retract the latch bolt by means of the lever 20, and then dog it in the retracted position.

Referring to Fig. 4, it will be noted that the parts are so arranged that when the rollback 27 is rotated in the opposite direction, the latch bolt may be released, as previously described. However, when the latch bolt has been dogged in the retracted position by means of the master key 40, the change key 39 is ineffective to release the bolt, because said change key rotates both rollbacks 27 and 29 on the axis of the sleeve 25, and in this case the rollback 27 will clear the lever 25, as shown in Fig. 6, being incapable of reaching the same. It will be understood, therefore, that while the change key 36 is always capable of retracting the latch bolt, it is incapable of dogging it in the retracted position. The master key 40, however, will not only retract the latch bolt, but will dog it in the retracted position owing to the fact that the master key actuates the detent lever 25 as well as the re-

tracting lever 20. The release of the latch bolt from its dogged position is also confined to the master key owing to the fact that when the change key is rotated in a 5 clockwise direction with respect to Fig. 1, neither rollback will be operative to release the detent lever.

I have not attempted to describe all of the modifications of the construction which 10 may be adopted within the scope of the invention as defined in the claims.

I do not claim herein the specific means for retracting the latch bolt from one side of the door by means of a key acting on a 15 detent member, as set forth in my co-pending application, Serial No. 710,570; nor do I claim broadly herein a lock having a latch bolt, a retracting member therefor, a detent member for dogging the bolt in retracted 20 position, a key to operate both of said members, and a key to operate the retracting member alone, as claimed in another co-pending application Serial No. 804,215.

What I claim is:—

25 1. In a lock, a latch bolt, retracting mechanism therefor, detent mechanism for dogging the bolt in retracted position, a cylinder lock at one side of the door, a key for said cylinder lock adapted to retract the latch bolt and dog it in retracted position, and another key for said cylinder lock operative to retract the latch bolt but inoperative to dog it in retracted position; substantially as described.

30 2. In a lock, a latch bolt, retracting mechanism therefor, detent mechanism for dogging the bolt in retracted position, a cylinder lock, a key operative on said retracting mechanism and on said detent mechanism 40 through said cylinder lock, and another key operative on said retracting mechanism alone through said cylinder lock; substantially as described.

35 3. In a lock, the combination of a latch bolt, a cylinder lock at one side of the door, a plurality of keys adapted to said cylinder lock, and mechanism operable by one of said keys to retract the latch bolt and dog it in retracted position, said mechanism being operative by another of said keys to the extent of retracting the bolt, but inoperative by said second key to dog the bolt; substantially as described.

40 4. In a lock, the combination of a latch bolt, a cylinder lock, a plurality of rollbacks operable by said cylinder lock, means actuated by one of said rollbacks to dog the latch bolt in retracted position, and means actuated by another rollback to retract the bolt, but inoperative to dog it in retracted position; substantially as described.

45 5. In a lock, the combination of a latch bolt, a cylinder lock, two rollbacks carried by said cylinder lock and forming permanent parts thereof, means operable by one

of said rollbacks to dog the latch bolt in retracted position, and means operable by the other rollback to retract the bolt without dogging it in retracted position; substantially as described.

70

6. In a lock, the combination of a latch bolt, a cylinder lock, two rollbacks carried by said cylinder lock, means actuated by one of said rollbacks to retract the bolt, and means actuated by the other rollback to dog 75 the bolt in retracted position; substantially as described.

75

7. In a lock, the combination of a case, a latch bolt therein, a cylinder lock secured to the case at the outside of the door, two rollbacks carried by said cylinder lock within the case, means actuated by one of said rollbacks to retract the bolt and dog it in retracted position, and means actuated by the other rollback to retract the bolt without 80 dogging it in retracted position; substantially as described.

80

8. In a lock, a latch bolt, a cylinder lock, a plurality of keys adapted to said cylinder lock, and mechanism operable by one of 90 said keys to retract the bolt and hold it retracted, and operable in part by another of said keys to retract the bolt without holding it retracted; substantially as described.

90

9. In a lock, a latch bolt, retracting mechanism therefor, detent mechanism for dogging the bolt in retracted position, a cylinder lock, a key for said cylinder lock operative on both of said mechanisms, and another and different key for said cylinder lock operative on said retracting mechanism alone; substantially as described.

95

10. In a lock, a latch bolt, retracting mechanism therefor, mechanism for dogging the bolt in retracted position, a cylinder lock 105 having a key plug and a sleeve surrounding the key plug, a rollback actuated by the key plug, and a rollback actuated by the sleeve, one of said rollbacks operative on both the retracting mechanism and the dogging mechanism, and the other rollback operable on the retracting mechanism alone; substantially as described.

105

11. In a lock, a latch bolt, retracting mechanism therefor, mechanism for dogging 110 the bolt in retracted position, a rollback to actuate the dogging mechanism, and a rollback to actuate the retracting mechanism, in combination with a cylinder lock having a key plug mounting one of said rollbacks, 120 and provided with a sleeve surrounding the key plug and mounting the other rollback; substantially as described.

110

12. In a lock, a latch bolt, a retracting lever therefor, and a detent lever adapted 125 to operate the retracting lever, in combination with a cylinder lock having a rollback to operate said levers together, and another rollback to operate the retracting lever independently; substantially as described.

130

13. In a lock, the combination of a latch bolt, pin tumbler lock mechanism, a plurality of keys adapted to said pin tumbler lock mechanism, and mechanism operable by one of said keys to retract the latch bolt and dog it in retracted position, said mechanism being operative by another of said keys to the extent of retracting the bolt, but inoperative by said second key to dog the bolt in retracted position, said second key being also inoperative to release the bolt from its dogged position; substantially as described.
14. In a lock, a latch bolt, retracting mechanism therefor, detent mechanism for dogging the bolt in retracted position, pin tumbler lock mechanism, a key operative on said retracting mechanism and on said detent mechanism, through said pin tumbler lock mechanism, and another key operable on said retracting mechanism alone, through said pin tumbler lock mechanism, said latch bolt being releasable from its dogged position only by means of said first key; substantially as described.
15. In a lock, a latch bolt, retracting mechanism therefor, detent mechanism for dogging the bolt in retracted position, a key to retract the latch bolt, dog it in retracted position, and release it from dogged position, and another key operative to retract the latch bolt but inoperative to dog it in retracted position, or release it from its dogged position; substantially as described.
16. In a lock, a latch bolt, a retracting lever therefor, a detent lever adapted to operate the retracting lever, and a pin tumbler lock mechanism having a rollback to operate the detent lever, and another rollback to operate the retracting lever independently, said detent lever being inoperative in either

direction by said second rollback; substantially as described.

17. In a lock, a latch bolt, retracting mechanism therefor, detent mechanism for dogging the bolt in retracted position, a pin tumbler lock mechanism having two rollbacks, a key operative on one of said rollbacks to dog the bolt in retracted position, and a second key operative on the other rollback to retract the bolt without dogging it in retracted position, said second key being inoperative to release the bolt from its dogged position; substantially as described.

18. In a lock, the combination of a latch bolt, a cylinder lock, two rollbacks carried by said cylinder lock, means actuated by one of said rollbacks to retract the bolt, and means actuated by the other rollback to dog the bolt in retracted position, said bolt being releasable from its dogged position by said second rollback only; substantially as described.

19. In a lock, the combination of a case, a latch bolt therein, a cylinder lock secured to the case, two rollbacks carried by said cylinder lock within the case, means actuated by one of said rollbacks to retract the bolt, and dog it in retracted position, and to release the bolt from its dogged position, and means actuated by the other rollback to retract the bolt without dogging it in retracted position, said other rollback being inoperative to release the bolt from its dogged position; substantially as described.

In witness whereof, I have hereunto set my hand on the 22nd day of October, 1914.
